WRAP-AROUND DRESS

Grace D. Durocher, St. Louis, Mo., assignor to
Forest City Manufacturing Company, St. Louis,
Mo., a corporation of Missouri

Application June 29, 1936, Serial No. 87,856

6 Claims. (Cl. 2—74)

This invention relates generally to feminine outer wear and has more particular reference to a dress of so-called wrap-around type, that is to say, a coat-like garment for feminine wear, in which, when the garment is worn, the front panels thereof overlap one another at the front of the figure.

Wrap-around dresses, as heretofore constructed, have been, so far as I am aware, loosely fitting garments more suitable for house wear than for the street, for the reason that, in the present state of the art, if a sufficient width of material is provided to afford an adequate lap of the front panels to render the garment suitable for street wear, the neck opening over the bust will gape badly at bent over positions of the body, with consequent exposure thereof, and while the waist may be cut low to avoid the gaping, such a low cut of the waist is required as to likewise result in excessive exposure of the body.

My invention has hence for its prime object the provision of a garment of the kind described, which is characterized in having its front panels of adequate width to render the garment suitable for street as well as house wear, yet nevertheless allows a higher cut of the waist for adequately covering the body while also neatly and snugly fitting the figure at bent-over positions of the body.

And with the above and other objects in view, my invention resides in the novel features of form, construction, arrangement, and combination of parts presently described and pointed out in the claims.

In the accompanying drawing,—

Figure 1 is a front elevational view, as dressed on the figure, of a wrap-around garment of my invention; and

Figure 2 is a detail plan view of the pattern of the garment of Figure 1, one of the front panels being shown attached at the shoulder seam to the back panel of the garment.

Referring now more in detail and by reference characters to the drawing, which illustrates a preferred embodiment of my invention, the garment includes a back panel A formed of a symmetrically gored back skirt-portion a and a fitted back waist-portion b, joined to the portion a at the waist seam 1', the portion b being made up from suitably fashioned and conjoined right and left side panels 1, 2, respectively, each having an arm cut-out 3, and a central panel 4 having a neck cut-out 5.

B, B', designate, respectively, the right and left front panels of the garment. Such panels

are made from the same pattern and a description of one will suffice for the other.

Each panel B, B', is cut from a single piece of material and extends for the full length of the garment, so as to comprise a front skirt-portion c and a front waist-portion d, respectively below and above the waist line of the garment, indicated by the dot-dash line 6 in Figure 2.

Each of the panels B, B', is formed for attachment of its side margin 7 to the corresponding side margin 7' or 7", as the case may be, of the back panel A, each of the front waist-portions d likewise having an arm cut-out 8 complementary to the arm cut-out 3 of the back waist-portion b.

The front panels B, B', are also joined to the back panel A at the respective shoulders of the garment, and, in forming the pattern of each panel B, B', the width of the material at the front shoulder margin 9 of the front waist-portion d is cut in excess, as at 10, of the width 15 of the corresponding back shoulder margin 11 of the back waist-portion b, and, when the waist-portion d is seamed, as at 12, to the waist-portion b, the excess material 10 is folded into the seam 12 as an unstitched tuck 13, for a purpose 20 presently appearing, the tuck 13 preferably being located in the seam 12 approximately an inch, more or less, and preferably not more than approximately one and one-half inches, from the neck opening 5 of the garment. 30

In Figure 2, the front panel B is shown as an illustration of the panel B, or the opposite panel B', as it is cut from the pattern and before it is attached to the back panel A, the final shape of the panel B being shown by the dot-dash 35 line 14.

The free margin 15 of the front waist portion d is cut with an excess of material 16, which includes the excess material 10 and forms a bulge or curvature in the margin 14, adjacent the waist line 6. The free margin 17 of the front skirt-portion c is likewise cut with an excess of material 18, which includes the excess material 15 and tapers from the waist line 6 to the bottom 40 of the skirt-portion c. 45

In Figure 2, the front panel B' is shown as an illustration of the panel B', or the opposite panel B, as it finally appears after attachment at the shoulder seam 12 to the back panel A. 50

The excess material 16, 18, of each panel B', or B, is taken up by means of an incomplete dart 19, which is formed with a replaceable line of stitching 20 in order that the girth of the garment may readily be adjusted to the waist 55

of the wearer thereof. The dart 19 has its upper end 21 open and disposed above the waist line 6, and extends below the waist line a suitable distance to form a closed end or point 22, the dart 5 19, together with the tuck 13, providing a breast-receptive fullness in the waist-portion *d*, as indicated by dot-dash lines 23 in Figure 2.

A tie or string 24 is attached to the free margin of each panel B, B', opposite the waist line 6, and each panel B, B', is provided with an eye or opening 25 disposed in the waist line 6 adjacent the side margin 7 of the panel.

Preferably, though not necessarily, the panels B, B', are first attached to the back panel A at the respective shoulder seams 12, and the garment is then completed by sewing the front panel side margins 7 to the back panel side margins 7', or 7'', as the case may be.

The front panels B, B', are each adapted to 20 extend substantially across the front of the garment, the skirt-portion *c* being preferably symmetrically gored, and the width of the panel at the waist line 6 being selected to approximately equal the length of the waist line from hip to hip 25 across the front of the figure of the wearer of the garment.

In the wear of the garment, the front panels B, B', are adapted to reside in overlapping relation across the front of the figure, the tie 24 of the 30 underlying panel, as B', being passed through the eye 25 of the overlying panel, as B, the pair of ties 24 being brought around to meet at the back of the wearer, where they are suitably separably knotted together, as is customary in the wear of 35 wrap-around garments.

As a result of such overlapping of the panels B, B', the free margins 15 of the respective front waist-portions *d* are adapted to extend crosswise of each other, each diagonally across the front 40 of the figure from the one shoulder substantially to the opposite hip thereof, and in so doing to complete the neck opening of the garment, as shown at 26 in Figure 1.

Sleeves 27 may likewise be fitted to the arm-openings formed by the arm cut-outs 3 and 8, and the sleeves 27 may take any desired form as 45 may best suit the intended purpose.

Heretofore, so far as I am aware, wrap-around garments have been characterized by a looseness 50 at the neck opening, which results, as I have previously stated, in excessive exposure at bent-over positions of the body, and I might add that such looseness occurs even in those cases where it is attempted to provide a fullness below the bust 55 by the formation of darts or pleats in the waist line of the garment.

I have found, however, that, by providing the fullness above the bust, as by the tuck 13, as well 60 as below the bust, as by the dart 19, the diagonal margin 15 of the waist-portion *d* will snugly and smoothly fit the curvature of the figure and will not gape or bulge at bent-over positions of the body.

This characteristic of the garment makes it 65 possible to cut the waist margin 15 higher, so as to adequately cover the bust of the figure, and also to employ such a wider over-lap of the front panels B, B', as to provide a double thickness of dress material across approximately the entire 70 width of the figure, forming a so-called "shadow-proof" lap substantially from said seam to side seam of the garment, all of which several features of my garment most obviously inures to the satisfaction of, and avoids any discomfiture to, 75 the wearer thereof.

The garment is simple and inexpensive in manufacture, is readily dressed on the figure, yet withal fits it neatly and comfortably, and is economical in wear, since the respective panels B, B', may be alternatively exposed on the outer 5 lap when the other panel has become soiled.

It will be understood that changes and modifications in the form, construction, arrangement, and combination of the several parts of the dress-garment may be made and substituted for those 10 herein shown and described without departing from the nature and principle of my invention.

Having thus described my invention, what I claim and desire to secure by Letters Patent is,—

1. In a feminine dress-garment, in combination, a back panel, a front panel attached at side and shoulder seams to the back panel, the width of the material for the shoulder seam of the front panel being in excess of the width of the material for the same seam of the back panel, 20 and the excess material being folded into the shoulder seam as an unstitched tuck to provide a bust-receptive fullness in the front panel therebelow.

2. A woman's wrap-around dress comprising a 25 back-panel, and a plurality of overlying front panels attached to the back panel at a shoulder seam, each front panel having a tuck at the shoulder seam and a vertically aligned tuck at the waist line for co-operatively providing a bust- 30 receptive fullness in said panel therebetween.

3. A woman's wrap-around dress comprising a back panel, and a plurality of front panels attached to the back panel at a shoulder seam, each front panel having a downwardly opening 35 vertical tuck at the shoulder seam and a vertically aligned upwardly opening tuck at the waist line for co-operatively providing a bust-receptive fullness in the panel therebetween.

4. A woman's wrap-around dress comprising a 40 back panel, and a plurality of front panels attached to the back panel, each of said front panels being cut initially of greater width than the normal body-covering requirements of the panel, said excess width in each of said panels 45 being folded in to reduce the said panels to normal body-covering size by the formation at the shoulder seam and the waist line of a pair of vertically aligned upwardly opening V-shaped tucks.

5. In a feminine dress-garment, in combination, a back panel, a front panel attached at side and shoulder seams to the back panel, the width of the material for the shoulder seam of the front panel being in excess of the width of the material for the same seam of the back panel, the excess material being folded into the shoulder seam as an unstitched tuck, the front panel being also cut in excess of material for the required width 55 at the waist line, said excess material being folded at the waist line into an upwardly flaring tuck unstitched at its upper end and disposed in vertical alignment with the shoulder tuck for providing a bust-receptive fullness in the front panel.

6. A wrap-around dress-garment comprising, in combination, a back panel, and a pair of front panels adapted to overlap substantially across the front of the figure when the dress is worn, each front panel being attached to the back panel at 70 respective side and corresponding shoulder seams, the width of the material for the shoulder seam of each front panel being in excess of the width of the material for the same shoulder seam of the back panel, each front panel having its upper 75

margin shaped for extending diagonally across the bust from the shoulder to the opposite hip, and the excess material at the shoulder being folded into the shoulder seam as an unstitched tuck, the front panel being also cut in excess of material for the required width at the

waist line, said excess material being folded at the waist line into an upwardly flaring tuck unstitched at its upper end and disposed in vertical alignment with the shoulder tuck for providing a bust-receptive fullness in the front panel. 5
